REMOVABLE CAP ATTACHMENT

Filed Oct. 16, 1922

INVENTOR
George W. Ittner,
BY
Philip C. Koch
ATTORNEY

UNITED STATES PATENT OFFICE.

GEORGE W. ITTNER, OF ST. LOUIS, MISSOURI, ASSIGNOR OF ONE-HALF TO JOHN B. HULETT, OF NEW YORK, N. Y.

REMOVABLE-CAP ATTACHMENT.

Application filed October 16, 1922. Serial No. 594,947.

To all whom it may concern:

Be it known that I, GEORGE W. ITTNER, a citizen of the United States, and a resident of the city of St. Louis and State of 5 Missouri, have invented certain new and useful Improvements in Removable-Cap Attachments, of which the following is a specification, reference being made to the accompanying drawings, forming a part 10 thereof.

My invention relates particularly to that type of removable caps which are rotatably secured upon a screw-threaded nozzle comprising the open end of compressible tubes 15 or receptacles for viscous substances such as tooth paste, shaving creams and the like, and the objects of my invention are, among other things, to provide an improved means for attaching the cap to the receptacle or 20 nozzle to prevent loss of the cap when removed or detached. For this purpose I have devised an improved link attachment for the cap which acts somewhat as a hinge or flexible joint with respect to the open 25 nozzle by which the cap is allowed a free to and fro movement from the nozzle only in a plane substantially coincident with the axes of the cap and nozzle. Such attachment holds the cap clear from the nozzle 30 when the tube is to be compressed in use, and yet readily permits the cap to be brought back into screwing-on position. Furthermore, my improved attachment may be easily sprung on or off both 35 the cap and nozzle, and is rotatably or slidably secured to both members while it may be rigidly held with either nozzle or cap while the one or the other is being rotated. Another feature of my invention is that the 40 attachment may be economically manufactured for tubes or caps of any size and also for nozzles of varying lengths by incorporating additional links in the attachment.

With these and other objects in view, my 45 invention comprises the novel construction, combination and arrangement of parts to be hereinafter specifically described, and thereafter particularly pointed out in the 50 appended claims.

I attain the foregoing advantageous results by the cap attachment a preferred embodiment of which is illustrated in the accompanying drawings in which—

Fig. 1 is a side elevation showing the 55 cap in position to close the nozzle of the tube receptacle;

Fig. 2 is a similar view showing the cap removed;

Fig. 3 is an enlarged side elevation view 60 with the cap and nozzle shown in vertical section; and

Fig. 4 is an enlarged top plan view with the parts in the position shown in Fig. 2.

Similar numerals refer to similar parts 65 throughout the several figures.

Referring to the drawings, the tube or receptacle 5 has the shoulder 6 at its upper or open end terminating in the nozzle 7 provided with the opening 8 through which 70 the contents of the tube 5 passes when the latter is compressed. The nozzle 7 is exteriorly screw-threaded at 9 and between the shoulder 6 and threads 9 I form the annular groove 10 about the base of the 75 nozzle 7. The cap 11 has the depending circular flange 12 interiorly threaded as shown in Fig. 3 to cooperate with the nozzle threads 9 to hold the cap 11, when rotated, to the nozzle 7. Encircling the flange 80 12 is the annular groove 13 adapted to rotatably or slidably secure the ring or loop portion 14 of the rectangular link 15, preferably formed of steel wire or other resilient material. Pivotedly secured to the ends 85 16 of the link 15 is the rectangular link 17 of similar material which is likewise pivotedly secured to the ends 18 and 19 of the ring 20 which is rotatably or slidably secured in the annular groove 10 at the base 90 of the nozzle 7 as shown in Fig. 4. By this series of pivoted rectangular links 15 and 17 with the connecting ring 20, the cap 11 is secured to, and is rotatable laterally about, the nozzle 7, while the cap 11 95 itself may be twisted or turned in loop portion 14 of the link 15. Again the cap 11 has a free movement to and from the nozzle 7 only in a plane substantially coincident with that of the axes of the nozzle 100 7 and cap 11. Additional links may be embodied in my link attachment holding the cap 11 to the base of the nozzle 7 to accommodate for tubes having nozzles of greater length than that shown. The ring 105 20 is readily inserted on the nozzle 7 by rotating same through the screw-threads 9 until it snaps into position in the groove

10 and likewise the loop portion 14 may be readily sprung open to remove the cap 11 from the link 15.

In operation, the cap 11 is unscrewed 5 and when removed is held in the position shown in Figs. 2 and 4, the links 15 and 17 constituting a flexible joint or hinge to hold the cap away from the nozzle 7 as shown. When the cap 11 is to be replaced, 10 it is raised in substantially a vertical plane, and the links 15 and 17 are folded upon each other as shown in Figs. 1 and 3, and the cap is screwed home.

It will be understood that the removable 15 cap attachment herein shown and described may be variously modified in details without departing from the principle and scope of my invention as defined in the claims.

I claim as my invention:

- 20 1. The combination with a part to be covered, of a cap therefor, and flexible means for loosely attaching said cap to said part, comprising a plurality of link members transversely hinged in spaced relationship to both part and cap with the end members 25 rotatably secured to each, whereby said cap may have a bodily movement to and from said part only in a plane substantially coincident with the axes of the cap and part.
- 30 2. A receptacle having an exteriorly screw-threaded nozzle, an interiorly threaded cap

for said nozzle, and means comprising a series of rectangular links transversely hinged in spaced relationship to both cap and nozzle for loosely attaching the cap to 35 said nozzle, the end links being rotatably secured around the cap and nozzle.

3. A receptacle having an exteriorly screw-threaded nozzle with an annular groove about its base, an interiorly threaded cap 40 for said nozzle having an annular groove externally cut therein, and pivoted link means slidably secured in said grooves for loosely attaching said cap to said nozzle and transversely hinged in spaced relationship 45 to both, said means permitting said cap to be moved to and from said nozzle only in a substantially vertical plane therewith.

4. A receptacle having an exteriorly screw-threaded nozzle with an annular groove 50 about its base, an interiorly threaded cap for said nozzle having an annular groove externally cut therein, and a series of rectangular links transversely pivoted at their spaced-apart corners, the end links being 55 slidably secured in said grooves for loosely attaching said cap to said nozzle to permit of a to and fro movement therebetween only in a plane substantially coincident with the axes of said cap and nozzle.

GEORGE W. ITTNER.
